UNITED STATES PATENT OFFICE

150,101

DESIGN FOR A VEHICLE

Robert C. Wallace, Indianapolis, Ind., assignor to Marmon-Herrington Company, Inc., Indianapolis, Ind., a corporation of Indiana

Application May 1, 1946, Serial No. 129,203

Term of patent 7 years

(Cl. D14—3)

To all whom it may concern:

Be it known that I, Robert C. Wallace, a citizen of the United States and a resident of Indianapolis, in the county of Marion and State of Indiana, have invented a new, original, and ornamental Design for a Vehicle, of which the following is the specification, reference being had to the accompanying drawings, forming part thereof, wherein:

Figures 5 and 6 are perspective views.

The characteristic features of the invention reside in the back door panel construction and its location and arrangement with regard to the back of the vehicle, as shown in Figure 4, and the construction and arrangement of the front fenders comprising the separate side and front fenders as particularly illustrated in Figures 1 and 2.

I claim:

The ornamental design for a vehicle, substantially as shown and described.

ROBERT C. WALLACE.
